Application June 11, 1936, Serial No. 84,636

8 Claims. (Cl. 229—8)

This invention relates to the fabrication of boxes, especially to boxes made of pasteboard or like material, and more particularly to such boxes having a heart-shaped or other curvilinear or 5 irregular contour.

In the fabrication of such boxes, according to conventional methods, difficulty is experienced in performing by machinery a substantial part of the steps involved, for the reason that the edge 10 joint between the bottom wall and side wall of the container element of the box structure, and similarly the edge joint between the top wall and side wall of the cover element of the box structure, has to be made with varying degrees of 15 curvature, and, in the instance of heart-shaped boxes, must include a V-shaped point which constitutes an abrupt departure from curvilinear form, while the V-shaped notch at the apex between the upper lobes of the heart-shape, constitutes a somewhat different departure, involving even greater difficulties in fabrication. 20

One of the conventional structural components of each of the aforesaid elements of such a box usually consists of one or more elongated wall 25 strips of pasteboard, which are secured to the flat bottom member, or the flat top member, in various ways, among which, in an effort to solve the problem of conformity to the irregular contour already mentioned, it has been proposed to 30 provide a rectangular side strip notched along one edge, with the portions between said notches bent inwardly for attachment to the base sheet, around the periphery of which the notched strip is bent, the distances between said notches increasing along the sides of the box adjacent to 35 its point and decreasing along the sharper curves opposite the point.

The application of such a strip in use involves 40 certain difficulties, among which may be mentioned the need for providing means guiding the proper positioning of the strip about the bottom wall to prevent the strip from being placed in a position in which any one of the tongues crosses 45 the sharp corner formed by the notch at the curved apex region at the top of the heart.

More than ordinary skill is also required in combining the notched strip with its associated parts in the fabrication of the box by the aforesaid method.

50 Under such conditions it is the general object of the present invention to provide a novel method of fabricating such boxes which makes it possible to press up in a single operation a base member for the container element, or a top member for the cover element, as the case may be,

which not only is of the desired curvilinear contour, with intervening irregular breaks in the curvature, such as the point and the notched apex of the heart, for a heart-shaped box, but which also includes, as an integral part of its 5 structure, an upright wall portion adapted to serve as a component of the side wall of the container element, or as a component of the side wall of the cover element, respectively.

A further object is to provide such a combined 10 bottom member and side component, and likewise such a combined cover member and side component that, in each instance, the other side components of the member can be applied in the form of suitable lengths of stock strip material, such as pasteboard, or any other suitable 15 strength-giving material, such as a strip having a glossy or a matte surface, of any desired color, the work being done by operatives of no greater than average skill or training, and certain steps 20 being performable by the use of suitable mechanism, with incidental economy in fabrication.

As a summary of the above objects, it is the 25 outstanding object of the invention to provide, in a method of fabricating boxes of the class described, the step of die-pressing a blank of sheet material to form around its periphery an upright flange of given height and having folds therein at suitable intervals to compensate for the presence 30 of excess material in the flange, the step of attaching to the side wall component so formed a band adapted to serve as an extension side wall component of sufficiently greater height to surround completely the exterior side of the first-named component, and to extend above the same 35 to the desired height of the complete wall, and the step of attaching to said band a strip of finish material, folded over the free edge or rim of the band and covering completely the outer side thereof, and extending down within the side wall to, and over, the region of the inner peripheral joint.

Other objects and features of the invention will 40 be pointed out as the description of the particular physical embodiment selected to illustrate the 45 invention proceeds.

In the accompanying drawings, like characters of reference have been applied to corresponding parts throughout the several views making up the drawings, in which:

Fig. 1 is a view in perspective of a blank of sheet material adapted to be used in pressing up a bottom component, or a top component of a heart-shaped box, according to the method of the present invention;

Fig. 2 is a view in perspective of the component after the pressing operation:

Fig. 3 illustrates in perspective the component of Figs. 1 and 2, and a side strip component, 5 ready for assembling;

Fig. 4 illustrates in perspective the components of Fig. 3 after assembly;

Fig. 5 is a fragmentary detail view in side elevation, illustrating a finish strip component with 10 an edge fold and gummed area, ready for application to the structure of Fig. 4;

Fig. 6 shows a completed component, capable of being used either for a container component or a cover component, according to its size;

15 Fig. 7 is a view in transverse, vertical section, on an enlarged scale, of a box composed of a container component and a cover component, of appropriate size, respectively, to fit together telescopically and each embodying the structure illustrated in the preceding figures, fabricated 20 according to the method of the present disclosure; this view illustrating also in dotted lines masks of desired form and contour, applied to the foundation box structure.

25 In a now-preferred embodiment of the invention selected for illustration and description, the part designated by the reference character 11 is a blank of sheet material, such as pasteboard, die-cut to the shape of a heart, which is the 30 illustrative example of a contour intended to be fabricated in the present instance. This blank may, or may not, have a score line 12 to facilitate the next step, viz., that of bending up the edge, in pursuance of the invention, which step may 35 be performed with suitable dies, in a die press (not shown).

40 Fig. 2 shows the blank of Fig. 1 after having been pressed to form an upright flange 13, of less height preferably than that which the side wall of the completed box is intended to have, 45 this flange constituting a structural element of the side wall. Its material is folded at intervals, by the pressing operation, as indicated at 14, so that the compensation for the transition from the flat state of the blank to the curvilinear wall shape is effected by thus infolding and compressing the marginal material of the blank in the area defined by the edge 16 thereof and the 50 crease line 12, whether the latter be actually scored, or imaginary.

55 This step is performed by machinery on the main structural component of the box and produces a wall element 17 conjoined integrally with the base 11 in the strongest possible manner, in contradistinction to the method of cutting specially shaped and spaced notches into a flange forming part of a wall strip which is thereafter adhered to the bottom of the box in an operation requiring unusual skill, training and dexterity, as has been already noted briefly, in the opening paragraphs of the present specification.

60 According to the present method, the next step consists in assembling with the side wall flange 17 a structural wall element 18 comprising, as 65 illustrated in Fig. 3, a strip of suitable material, such as pasteboard, of uniform continuity and width from end to end, its width being preferably that of the intended height of the side wall in the completed box component, whether the 70 same is to be used for the container component or the cover component.

75 The strip 18 is preferably gummed entirely over the face 19 that is to be applied around the exterior circumference 20 of the component 11, to facilitate adhering the strip to the flange 17,

an operation which can be performed either manually or by machine, the length of the strip 18 being suitable to form a closed joint at the desired point on the periphery of the box, as at the point 21, where, in the instance illustrated in 5 Fig. 4, the end 22 is lapped over, and adhered to, the end 23.

It will be noted that, in the original blank 11, as shown in Fig. 1, the edge of the blank is formed with a notch 24 at the point, and with a 10 slit 25 at the apex, the first being designed to facilitate an accurate meeting of the various uprights edges at the point region 21, and the notch 25 being designed to facilitate the formation of a neat clearly defined upright line 26 at 15 the apex of the heart (see Figs. 4, 6, and 7).

The main structural elements of the box component having thus been assembled, as shown best in Fig. 4, the next step in fabrication of the component is to apply thereto a finish strip 27, 20 which may desirably be made of enamelled paper, having its entire surface gummed on the side 28, which is to be contiguous to the edge 13 and adjoining faces 17 and 27 of the flange, the strip being of sufficient extent to cover the entire outer 25 face 17 of the side wall and at least that portion of the inner wall which includes the inner peripheral joint 30 between the flange and the band.

After the finish strip has been applied, the component presents the appearance shown in 30 Fig. 6, and constitutes a complete structural entity, whether it is to be used as a container, or as a cover element of the box.

It may be further reinforced, or supplemented, by securing thereto, as by pasting, a mask, as 35 31 indicated by dotted lines in Fig. 7, which shows a flat base of sheet material for the container component, which is designated generally by the reference character C' in this figure; and a mask 32, similarly shown in dotted lines in Fig. 7, may 40 be secured to the cover component, therein designated C''. This cover mask is adorned with an embossed portion 33 of known form, and of course a great variety is permissible in the contour, color and finish characteristics of such masks, 45 which are well known in the art.

We claim:

1. As a new article of manufacture, a component for a box of the class described, comprising a heart-shaped blank of sheet material having 50 around its periphery a pressed-up integral flange, said flange having folds therein at intervals compensating for excess material in the peripheral edge portion of said blank, constituting said flange, said flange having a slit at substantially 55 the point of the heart, and a V-shaped notch at substantially the apex of the heart, a band attached to the outer face of said flange, said band serving as an extension side wall element of sufficiently greater height than said flange to 60 surround completely the exterior side of the flange and to extend beyond the same to the desired height of the complete wall constituted of said flange and said band, and a strip of finish material attached to said band covering completely the outer face of the band and extending downwardly within the side wall formed by the flange and band, to, and over, the inner peripheral joint between the band and the flange.

2. As a new article of manufacture, a box of 70 the class described, comprising a container component and a cover component, each constituted as set forth in claim 1, said components being assembled in complementary, telescopic relation with each other, said box being further charac- 75

- terized by a flat mask applied to the bottom exterior face of said container component and a like mask having an embossed body part and attached to the top face of said cover.
5. 3. As a new article of manufacture, a component for a box of the class described, comprising a heart-shaped blank of sheet material having around its periphery a pressed-up integral flange, said flange having a slit at substantially the point of the heart, and a V-shaped notch at substantially the apex of the heart, a band attached to the outer face of said flange, said band serving as an extension side wall element of sufficiently greater height than said flange to surround completely the exterior side of the flange and to extend beyond the same to the desired height of the complete wall constituted of said flange and said band, and a strip of finish material attached to said band covering completely the outer face of the band and extending downwardly within the side wall formed by the flange and band.
10. 4. As a new article of manufacture, a box of the class described, comprising a container component and a cover component, each constituted as set forth in claim 3, said components being assembled in complementary, telescopic relation with each other, said box being further characterized by a flat mask applied to the bottom exterior face of said container component and a like mask having an embossed body part and attached to the top face of said cover.
15. 5. As a new article of manufacture, a component for a box of the class described, comprising a heart-shaped blank of sheet material having around its periphery a pressed-up integral flange, said flange having means therein at intervals compensating for the excess length of the peripheral edge portion of said blank, constituting said flange, said flange having a slit at substantially the point of the heart, and a V-shaped notch at substantially the apex of the heart, a band attached to the outer face of said flange, said band serving as an extension side wall element of sufficiently greater height than said flange to surround completely the exterior side of the flange and to extend beyond the same to the desired height of the complete wall constituted of said flange and said band, and a strip of finish

material attached to said band covering completely the outer face of the band and extending downwardly within the side wall formed by the flange and band, to, and over, the inner peripheral joint between the band and the flange.

6. As a new article of manufacture, a component for a box of the class described, comprising a substantially heart-shaped body of sheet material having around its periphery a pressed-up integral flange, such flange having a slit at substantially the point of the heart, and a slit at substantially the apex of the heart, a band attached to the outer face of said flange, said band serving as a side wall element and surrounding completely the exterior side of the flange, and a strip of finish material attached to said band, covering completely the outer face of the band and extending downwardly within the side wall formed by the flange and the band.

7. As a new article of manufacture, a box of the class described, comprising a container component and a cover component, each constituted as set forth in claim 6, said components being assembled in complementary, telescopic relation with each other, said box being further characterized by a flat mask applied to the bottom exterior face of said container component and a like mask having an embossed body part and attached to the top face of said cover.

8. As a new article of manufacture, a component for a box of the class described, comprising a substantially heart-shaped body of sheet material having around its periphery a pressed-up integral flange, said flange being so formed at intervals therein as to compensate for the excess length of the peripheral edge portion of such sheet material constituting said flange, said flange having a slit at substantially the point of the heart and a slit at substantially the apex of the heart, a band attached to the outer face of the said flange, said band serving as a side wall element with said flange and surrounding completely the exterior side of the flange, and a strip of finish material attached to said band, covering completely the outer face of the band and extending downwardly within the side wall formed by the flange and the band.

ANTHONY DI DOMENICO.
